(57) CLAIM

We claim the ornamental design for a display screen or portion thereof with graphical user interface, as shown and described.

DESCRIPTION

FIG. 1 is a front view of a display screen or portion thereof with graphical user interface showing our new design;

FIG. 2 is a front view of the design of FIG. 1 shown in a different environment;

FIG. 3 is a front view of the design of FIG. 1 shown in a different environment;

FIG. 4 is a front view of the design of FIG. 1 shown in a different environment;

FIG. 5 is a front view of the design of FIG. 1 shown in a different environment;

FIG. 6 is a front view of the design of FIG. 1 shown in a different environment;

FIG. 7 is a front view of the design of FIG. 1 shown in a different environment;

FIG. 8 is a front view of the design of FIG. 1 shown in a different environment;

FIG. 9 is a front view of the design of FIG. 1 shown in a different environment;

FIG. 10 is a front view of the design of FIG. 1 shown in a different environment;

FIG. 11 is a front view of the design of FIG. 1 shown in a different environment;

FIG. 12 is a front view of the design of FIG. 1 shown in a different environment;

FIG. 13 is a front view of the design of FIG. 1 shown in a different environment;

FIG. 14 is a front view of the design of FIG. 1 shown in a different environment;

FIG. 15 is a front view of the design of FIG. 1 shown in a different environment;

FIG. 16 is a front view of the design of FIG. 1 shown in a different environment;

FIG. 17 is a front view of the design of FIG. 1 shown in a different environment;

FIG. 18 is a front view of the design of FIG. 1 shown in a different environment;

FIG. 19 is a front view of the design of FIG. 1 shown in a different environment;

FIG. 20 is a front view of the design of FIG. 1 shown in a different environment;

FIG. 21 is a front view of the design of FIG. 1 shown in a different environment;

FIG. 22 is a front view of the design of FIG. 1 shown in a different environment;
FIG. 23 is a front view of the design of FIG. 1 shown in a different environment;
FIG. 24 is a front view of the design of FIG. 1 shown in a different environment;
FIG. 25 is a front view of the design of FIG. 1 shown in a different environment;
FIG. 26 is a front view of the design of FIG. 1 shown in a different environment;
FIG. 27 is a front view of the design of FIG. 1 shown in a different environment;
FIG. 28 is a front view of the design of FIG. 1 shown in a different environment;
FIG. 29 is a front view of the design of FIG. 1 shown in a different environment;
FIG. 30 is a front view of the design of FIG. 1 shown in a different environment;
FIG. 31 is a front view of the design of FIG. 1 shown in a different environment;

FIG. 32 is a front view of the design of FIG. 1 shown in a different environment;
FIG. 33 is a front view of the design of FIG. 1 shown in a different environment;
FIG. 34 is a front view of the design of FIG. 1 shown in a different environment;
FIG. 35 is a front view of the design of FIG. 1 shown in a different environment;
FIG. 36 is a front view of the design of FIG. 1 shown in a different environment;
FIG. 37 is a front view of the design of FIG. 1 shown in a different environment; and,
FIG. 38 is a front view of the design of FIG. 1 shown in a different environment.

The outermost broken lines in the Figures illustrate a display screen or portion thereof and form no part of the claimed design. The other broken lines in the Figures illustrate portions of the graphical user interface that form no part of the claimed design.
